UNITED STATES PATENT OFFICE.

JOHN G. JONES, OF ROCHESTER, NEW YORK, ASSIGNOR TO EASTMAN KODAK COMPANY, OF ROCHESTER, NEW YORK, A CORPORATION OF NEW YORK.

APPARATUS AND METHOD FOR MAKING PAPER STRIPS.

Application filed March 23, 1922. Serial No. 546,114.

To all whom it may concern:

Be it known that I, JOHN G. JONES, a citizen of the United States of America, residing at Rochester, in the county of Monroe 5 and State of New York, have invented certain new and useful Improvements in Apparatus and Methods for Making Paper Strips, of which the following is a full, clear, and exact specification.

10 This invention relates to a machine and method for making long strips of paper with thin edges. Such strips are of use particularly in connection with the photographic film cartridges described in my Patents Nos. 15 1,454,812; 1,454,813; 1,454,814; 1,454,815; 1,454,816 and 1,454,817, granted May 8, 1923, although it is to be understood that the paper as such may be used for other purposes.

20 The objects of my invention are to provide a process by which a number of comparatively narrow long strips with thinned edges may be simultaneously formed and cut from a single strip of wide material, 25 which method will be capable of being carried out by a suitably designed apparatus, and to provide one form of apparatus which is capable of carrying out such a process with accuracy and speed. Other objects will 30 appear in the description which follows.

Reference will now be made to the appended drawing in which:

Fig. 1 is a side elevation with certain parts in section of a machine embodying my 35 invention;

Fig. 2 shows a fragment of a piece of paper illustrating the steps of the process;

Fig. 3 is a view of the buffing wheels, showing their relative positions;

40 Fig. 4 is a view of a single buffing wheel, and its corresponding anvil pulley;

Fig. 5 shows a transverse section of part of a strip of paper after it has been grooved, but before it has been cut;

45 Figs. 6 and 7 show modified forms of buffing wheels and their corresponding anvil pulleys.

In all of the figures the same reference characters are used throughout to denote 50 the same parts.

The figures are largely schematic and are not intended to show all the details of the finished machine, as these would obscure the features and combinations of parts in 55 which the invention resides. There is

shown, however, a completely operative mechanism, amply sufficient to enable any skilled designer to construct a machine.

A suitably shaped frame 1 supports the various operative parts of the machine. 60 This is extended at the top to form what is termed a "turtle-back" 2, comprising side flanges 3, of which one only is shown, between which extend idle rollers 4 indicated in section. These flanges act as guides to direct the paper to the mechanism hereafter to be described. A roll of material 5, which will usually be paper, is rotatably supported on the shaft 6 supported in suitable bearings 7 carried by a bracket 8 on the frame. The 70 paper 7 is drawn from this roll over an idle roll 8 and then over the rolls 4, and thence is passed to more closely arranged snubbing rolls 9, where the paper is drawn in a series of sharp turns, as shown in the drawing, 75 these snubbing rolls 9 being supported between the sides 3. Beneath the last snubbing roll 9 there are arranged a series of abrading wheels 10, each of which is mounted on the frame 1 by means permitting of its adjustment. As shown, there is provided for each abrading wheel 10 a fixed block 11 with a guide 12 which dovetails into a corresponding guideway in the transversely slid able member 13. Upon the member 13 there is 80 mounted a support 14 adapted to slide in a direction at right angles to the first mentioned movement. This block 14 supports, by means of brackets 15, the abrading wheel 10 on an axis 16. The second described motion is controlled by the hand screw 17 passing through the down turned end 18 of the slide 13 and bearing against the end of slide 14. The parts can be locked in adjusted 85 position by a bolt 19.

I prefer to mount these abrading wheels in a staggered relation, as shown in Fig. 3, mounting one series from downwardly extending supports, and the other series from similar upwardly extending supports, as this permits closer positioning of the abrading wheels. Opposite each of the abrading wheels is an anvil pulley 20 supported on shaft 21 carried between brackets 22 of a support 23 adjustable, by means of the bolt 24, on rod 25 common to all of the supports 23.

Upon the several shafts 16 there are mounted driving pulleys 26, from which there are run driving belts 27 to correspond- 110

ing driving pulleys 28 mounted on a shaft 29, this shaft being driven by suitable shafts and gearing 30 driven by motor 31. The abrading wheels 10 and their corresponding anvils 20 are so shaped as to form grooves in the paper passing between them in the form shown in Figs. 3 and 4. These abrading wheels are of greatest diameter at the central part of their periphery, as indicated at 32, and slope gradually to the edges, so that the grooves formed in the paper will be of the form indicated in Fig. 5. The anvil pulley used in this form has a straight cylindrical surface, as indicated in Fig. 4.

As shown in Fig. 5, the paper has formed therein at spaced intervals grooves 33 with sides inclining evenly, so as to give a shallow V shaped cross section. The dimensions shown in Fig. 5 are much exaggerated, since in practice the grooves would be normally spaced apart by a distance of several inches and the depth of the groove in comparison with its width would be very slight. For instance, in paper .004" thick, the groove would be possibly .002" deep, and $\frac{1}{4}$ " wide. These dimensions are given purely by way of illustration.

In Fig. 6 is shown another form of abrading and anvil rolls, in this case the abrading roll 34 having a straight periphery 41 and an anvil pulley 42 having its greatest diameter at its center 43 and inclining in each direction. In such a case the anvil roll would tend to bend the paper up toward the abrading wheel, which would thus wear off the upper surface. In Fig. 7 the abrading wheel 35 has a rounded surface 36, while the anvil wheel 37 has a plain periphery as before.

After passing the grooving means, the paper strip 7 passes around the idle rolls 39 and 40 and between a series of staggered slitting disks 44, thence over another idle roll to the driving rolls 46 and 47. These driving rolls are driven by suitably interacting gears 48 and 49 upon their shafts 50 and 51, shaft 50 being driven by gear 52 from gear 53 which is driven from the motor 31. The gear 53 also drives gear 54 which actuates the cutting disks by suitable mechanism. These cutting disks are carefully arranged in alignment with the several abrading wheels, so that they will slit the paper longitudinally and medially of the grooves formed therein, the paper being guided between the side walls 55, one only of which is shown. After leaving the roll 46, the paper, now in the form of comparatively narrow strips, passes over idle rolls 56 and 57, to the take-up rolls 58 and 59 driven by the belt 60 from a pulley 61 driven by motor 31. This belt drive constitutes a friction take-up, so as to maintain the paper under tension during winding and

permitting slip. The driving rolls 46 and 47 maintain the paper under tension back through the machine to the snubbing rolls 9 which, by reason of the sharp turn given to the paper, act as a sufficient resistance to the pull to maintain the proper tension.

In Fig. 2 a strip of paper 7 is shown, the upper part of which is indicated at 62 as uncut, and a series of grooves are formed in it, as indicated at 63, some beginning ahead of the others, because of the positions of the alternate abrading wheels. The cuts 64 are indicated in full lines in the center of these grooves. The continued dotted lines indicate the thin portion of the paper on each side of the central cut, so that at the lower end of this figure there is shown a series of strips having thinned edges. The outer edges of the outer strips are not thinned.

It is obvious that the process herein described can be carried out in a wide variety of ways, particularly as relates to the formation of a strip of paper with grooves therein, and that machines differing widely in structure and mode of operation from that herein shown may be employed. I contemplate as within the scope of my invention, all such alternate and modified processes and all such modifications and mechanical equivalents that can be utilized in machines of the character described, as fall within the terms of the following claims.

Having thus described my invention, what I claim as new and desire to secure by Letters Patent is:

1. The method of making strips of paper with thin flexible borders comprising the formation of shallow grooves in a strip of paper and slitting the paper in the grooves.

2. The method of making strips of paper with thin flexible borders that comprises forming spaced shallow grooves in a wide strip of paper and in slitting the paper in the grooves and longitudinally thereof.

3. The method of making strips of paper with thin flexible borders that comprises forming spaced parallel shallow grooves in a strip of paper and in slitting the paper medially and longitudinally of the grooves.

4. The method of making narrow strips of paper with thin flexible margins that comprises forming a wide strip of paper with spaced parallel shallow grooves, and slitting the paper longitudinally and medially of the grooves.

5. The method of making long narrow strips of paper with thin flexible borders that comprises taking a long wide strip of paper, removing material therefrom to form spaced, parallel grooves longitudinally thereof and in slitting the paper longitudinally and medially of the grooves in a continuous line.

6. The method of making strips of paper

- with thin borders comprising removing longitudinal portions of the paper stock from a paper strip previously manufactured with parallel surfaces to form longitudinal shallow grooves therein and slitting the paper in the grooves.
7. The method of making strips of paper with thin borders that comprises removing longitudinal portions of the paper stock 10 from one side of a long paper strip previously manufactured with plane surfaces, thereby forming longitudinal grooves in one surface thereof, and in slitting the paper medially and longitudinally of the grooves.
- 15 8. The method of making strips of paper with thin borders that comprises forming by abrasion grooves in a paper strip previously manufactured with plane surfaces, and slitting the paper in the grooves.
- 20 9. The method of making strips of paper with thin borders that comprises forming by abrasion spaced parallel grooves in a strip of paper and in slitting the paper medially and longitudinally of the grooves.
- 25 10. In a machine of the class described, means for drawing and guiding strip material therethrough, and two corresponding series of elements in longitudinal alignment past which the material is drawn, one adapted 30 to render thinner longitudinal bands in the material passing opposite it and the other adapted to slit the material longitudinally of the bands, whereby the edges of the resulting strips are rendered thin and flexible.
- 35 11. In a machine of the class described, means adapted to form spaced shallow grooves in a strip of paper, a corresponding series of slitting elements, and means to feed a strip of paper past said means to form 40 shallow grooves therein and past said elements to slit the paper longitudinally of the grooves.
12. In a machine of the class described, means adapted to remove bands of material 45 from a surface of a strip of paper, a series of slitting elements, and means for feeding and guiding a strip of paper past said means whereby a series of spaced parallel shallow grooves is formed therein, and past said elements whereby the paper will be slit longitudinally of the grooves.
13. In a machine of the class described, a series of pairs of cooperating elements between which a strip of paper may be drawn 55 and adapted to form shallow grooves in such paper, a corresponding series of slitting elements, and means for drawing a strip of paper between said first named elements and past said second named elements, whereby 60 the paper is first grooved and then slit longi-

tudinally of the grooves in a continuous line.

14. In a machine of the class described, a series of spaced abrading elements, and a corresponding series of slitting elements, 65 means for drawing a strip of paper past said abrading elements whereby a series of grooves is formed therein and then past said slitting elements whereby the paper is slit longitudinally of the grooves. 70

15. In a machine of the class described, a series of independently adjustable abrading elements, and a corresponding series of adjustable slitting elements, means for drawing a strip of paper first past said abrading 75 elements whereby a series of grooves is formed therein and then past said slitting elements whereby the paper is slit longitudinally of the grooves.

16. In a machine of the class described, 80 anvil means and a series of abrading means between which strip material may pass and by which grooves may be formed therein, and a corresponding series of slitting means in longitudinal alignment with the abrading 85 means, means for drawing and guiding strip material between the anvil and abrading means and past the slitting means.

17. In a machine of the class described, a series of spaced abrading wheels, a corresponding series of anvil pulleys, a corresponding series of slitting discs, means to draw and guide a strip of strip material between the wheels and pulleys to form 90 grooves therein and past said discs to slit 95 the material longitudinally of the grooves the wheels, pulleys and discs being mounted to rotate on axes lying transversely of the material and means to rotate said wheels, pulleys and discs. 100

18. In a machine of the class described, a series of independently adjustable spaced abrading wheels, a corresponding series of independently adjustable anvil pulleys each of which is but slightly spaced from its respective abrading wheel, a corresponding series of slitting discs located respectively in line with the abrading wheels, means for rotating said wheels, pulleys and discs, and means for drawing and guiding a strip of paper first between said wheels and pulleys whereby a series of separated parallel longitudinal grooves are formed therein, and then past said discs whereby the paper is slit longitudinally and medially of the 115 grooves to form strips having thinned margins. 110

Signed at Rochester, New York, this 18th day of March 1922.

JOHN G. JONES.
